UNITED STATES PATENT OFFICE.

CHARLES ROSS, JR., OF BROOKLYN, NEW YORK.

PAINT-MIXING MACHINE.

SPECIFICATION forming part of Letters Patent No. 348,931, dated September 7, 1886.

Application filed July 7, 1886. Serial No. 207,316. (No model.)

To all whom it may concern:

Be it known that I, CHARLES ROSS, Jr., a citizen of the United States, residing at Brooklyn, in the county of Kings and State of New York, have invented certain new and useful Improvements in Paint-Mixing Machines, of which the following is a specification, reference being had therein to the accompanying drawings, in which--

10 Figure 1 represents a perspective view of a paint-mixing machine provided with my improvement; Fig. 2, a detail, and Fig. 3 a detail of a modification.

This improvement relates to a device for 15 raising and lowering the mixer-arm in paint-mixing machines; and the invention consists in the peculiar combinations and the construction and arrangement of parts, hereinafter more particularly described, and then definitely pointed out in the claims.

Referring now to the details of the drawings, A represents the frame, B B' B" the bevel-gear, C C the fast and loose pulleys, D the stirrer, and E the pan, of an ordinary paint-mixing machine. The gear B runs on a shaft 25 that works in an arm, F, that is capable of sliding up or down on a vertical standard, G, that rises from the frame.

In practice it is necessary to lift the mixer 30 from the pan to allow of the substitution of one pan for another, and this has heretofore been done by means of a rope passing over a pulley or pulleys attached to a beam in a floor overhead. This is a very inconvenient and un- 35 mechanical contrivance, and to avoid the use of it is the object of my improvement. As the preferable means, I provide the standard with a rack, g, preferably sunk into the surface of the same, into which rack meshes a 40 pinion, H, (see Fig. 2,) firmly secured to a shaft, I, journaled in suitable bearings in the arm F, and having firmly fastened thereto a ratchet-wheel, J, and hand-wheel K. Pivoted to the back of the arm F is a pawl, L, which 45 takes into the teeth of the ratchet-wheel J. By this description it is obvious that by turning the hand-wheel K in the direction shown by the arrows the pinion H will be turned, which, as it takes into the rack g, will necessarily raise the arm F and stirrer D to any de-

sired extent, or so that it may be lifted clear of the pan, as shown in dotted lines, to allow of the removal of the latter when necessary, as when a fresh pan of paint is to take the place of the one already mixed. It will also 55 be evident that as the pawl catches in the teeth of the ratchet-wheel the arm and mixer will be firmly held in any desired position. When it is desired to lower the arm and stirrer, it is only necessary to raise the pawl L out of 60 the teeth of the ratchet-wheel, when the arm and mixer will descend by the force of gravity into the pan; but to prevent too rapid descent its motion can be controlled by the hand-wheel K. In some cases I may use a screw, 65 S, provided with a hand-wheel, T, which screw passes through an arm, U, attached to the column, and works in a female thread formed in the arm F. By this construction the arm may be raised or lowered, as desired; 70 but it will take a longer time to operate the same, and I therefore prefer the arrangement shown in Fig. 1.

It will be seen that by either of the constructions shown a very convenient and durable device is produced for raising and lowering the arm, which is always in position for use, and is fitted to the machine before it leaves the factory, whereas, where a rope and pulley are used, as has heretofore been practiced, 75 the rope and pulley must be placed in position after the machine is sent to its place of operation, and, moreover, it is not always convenient to find a place for setting the pulleys over which the rope passes, both of which 80 troubles are overcome by my improvements.

What I claim as new is—

1. The combination, in a mixing-machine, and with the arm F and standard C thereof, of a hoisting device mounted in one of said 90 parts and acting on the other, substantially as described.

2. The combination, in a mixing-machine, and with the arm F and standard G thereof, of a pinion working in a rack formed in or attached to said standard, and means, as the shaft I and hand-wheel K, for operating said pinion, substantially as described.

3. The combination, in a mixing-machine, of the standard G, having rack g, and the arm 100

F, provided with bearings for the shaft I, with
said shaft I, a pinion operating by it and
meshing in said rack, a ratchet-wheel connect-
ed with the pinion, and a pawl, L, catching
5 into said ratchet-wheel, substantially as de-
scribed.

In testimony whereof I affix my signature, in

presence of two witnesses, this 6th day of July,
1886.

CHARLES ROSS, JR.
